UNITED STATES PATENT OFFICE.

ALONZO KIMBALL MARSH, OF NEW YORK, N. Y., ASSIGNOR TO A. KIMBALL COMPANY,
OF NEW YORK, N. Y., A CORPORATION OF NEW YORK.

PIN TICKET.

Application filed August 3, 1922. Serial No. 579,440.

To all whom it may concern:

Be it known that I, ALONZO KIMBALL MARSH, a citizen of the United States, and resident of New York, county of New York, **5** State of New York, have invented an Improvement in Pin Tickets, of which the following description, in connection with the accompanying drawing, is a specification, like characters on the drawing representing **10** like parts.

This invention relates to improvements in marking devices, such as, pin tickets which are adapted to be secured to articles which are exposed for sale which have a detachable flap adapted to be folded against the back of the body of the pin ticket and to be retained in folded position between the body of the ticket and the article when the pin ticket is attached to the article and upon **15** **20** which flap notations, corresponding to the notations upon the pin ticket body, may be placed so that the flap may be detached and turned in to the office of the store as a sales record. The flap may also have placed upon **25** it confidential memoranda for the employees of the store.

The principal object of the invention is to provide an article of manufacture comprising **30** an integral strip consisting of a series of pin tickets with their flaps which may be detached along suitable weakened fold lines and used in the manner above described. Such strips of pin tickets can be readily packaged and transported and the pin tickets **35** detached from the strip as they are needed without danger of pricking and injuring the hands of the operator which sometimes occurs when usual types of pin tickets are removed from boxes in which they are mis- **40** cellaneously placed.

A preferred embodiment of the invention is illustrated in the accompanying drawing, in which,

Fig. 1 is a view of a section of a strip of **45** pin tickets and flaps embodying the invention;

Fig. 2 is a view illustrating the pin ticket embodying the invention as applied to the article to be marked;

Fig. 3 is a view of the pin ticket with the flap in extended position;

Fig. 4 is a perspective view of the back of the pin ticket showing the flap folded against the back; and,

Fig. 5 is a diagrammatic view of a strip **55** of pin tickets in the form of a roll.

The marking device or pin ticket embodying the invention comprises a ticket or body **60** 1 of cardboard or other suitable material preferably in the usual rectangular form of a pin ticket having a fastening device secured to it adjacent the upper end. The fastening device which is illustrated herein is of the usual type employed in the well known "Empire" ticket and comprises a **65** staple, the penetrating members or legs 2 and 3 of which pass through the ticket a short distance from the upper edge, the loop 4 of the staple being bent around the edge of the ticket and clamped against the under **70** face thereof as illustrated more fully in Fig. 4 of the drawing.

The ticket is provided with a laterally extending flap 5 which desirably is integral with the ticket and weakened fold lines 6 extending across the base of the flap in continuation of the edge 7 of the body of the ticket.

The body of the ticket and the flap desirably are provided with identical notations **80** so that the flap may be detached from the ticket and turned in to the office as a sales record of the article when sold, the body of the ticket being permitted to remain upon the article.

When the ticket is to be applied to the article, which usually is a textile article or material, the penetrating members of the fastening device are thrust through a portion of the article and bent laterally in the **90** customary manner. However, before the pin ticket is applied the flap 5 is folded against the back of the ticket so that when the ticket is applied to the article the fastening member, by holding the ticket in parallelism with and close to the face of the article, serves to clamp the flap between the body of the ticket and the article. Such clamping action occurs for the reason that the upper edge of the flap lies in proximity **95** to the fastening device and the fastening device, therefore, prevents the flap from

swinging to extended position even though same resilience remains in the material notwithstanding the weakening of the fold line.

When the flap is thus folded against the back of the ticket it is practically concealed so that the pin ticket presents its usual neat appearance.

As before stated, the body of the pin ticket and the flap desirably are provided with identical notations, but confidential data for the officers or employees of the store may also be placed upon the flap which is removed when the sale is made.

By reason of this construction a neat pin ticket is provided which not only contains all the capabilities of usual forms of pin tickets, but also provides a detachable member which may be filed as a memorandum of the sale.

20 A further feature of the invention consists in providing pin tickets of this character in the form of a strip and several advantages arise by reason of this construction. In the first place a series of tickets 25 are provided which can be readily and conveniently packaged as the strips can be coiled as illustrated in Fig. 5 and enclosed in a suitable carton so that the points of the fastening members will be protected from injury. In the second place the tickets can be readily detached from the strip as needed without danger of injuring the hands of the operator and when the desired number of pin tickets have been removed from the strip 30 35 the roll can be restored to its container so that the tickets and their fastening members may be protected from being soiled or injured when not in use. Third, pin tickets formed in a strip in the manner illustrated 40 45 can be readily passed through the usual type of printing machines for pin tickets and identical notations marked upon the flaps and body of the tickets so that pin tickets having such flaps can be readily and economically produced.

The formation of the strip of pin tickets consists first in cutting a strip of marking material, such as, paper, of the desired form for the ticket and flaps which, as illustrated herein, comprises alternating narrow sections 8 and wide sections 9 and producing weakened fold lines 10 at the junctions of the narrow and wide sections so that the strip will present a series of alternating ticket bodies 1 and flaps 5. The fastening members are secured to the upper ends of the ticket sections 1 in the usual manner by thrusting the limbs 2 and 3 of the penetrating members

through the extending end portions of the 60 ticket adjacent the edge thereof and folding the loop portion of the fastening member around the edge and against the under face of the ticket in the usual manner.

The strip may be rolled into spiral form 65 as illustrated in Fig. 5 and placed in a suitable carton for shipment. The strip may be fed by the user through a suitable marking machine and the desired notations 11 printed 70 successively upon the ticket sections and the 75 flap sections.

The width of the flap desirably is substantially the same as the width of the body of the ticket, but this is not wholly essential and it will be understood that the form of 75 the ticket, the width and length of the flap may be modified as may be found desirable.

It will also be understood that the preferred embodiment of the invention disclosed herein is illustrative and not restrictive and that other forms of tickets and flaps and other fastening means for securing the ticket to the article to be marked may be employed within the spirit and scope of the 80 following claims.

Having thus described my invention, what I claim as new, and desire to secure by Letters Patent, is:

1. An article of manufacture comprising a strip of paper having alternating narrow 90 sections and wide sections, said wide sections being provided adjacent their projecting ends with penetrating members, weakened fold lines extending transversely of said strip at the edges of said wider sections defining the contour of said wider sections as pin ticket bodies whereby severance upon the fold lines on the same side of successive wider sections will produce pin 95 tickets each having a laterally extending 100 flap.

2. An article of manufacture comprising a strip of paper having alternating narrow sections and wide sections of equal length, said wide sections being provided adjacent 105 their projecting ends with penetrating members, weakened fold lines extending transversely of said strip at the edges of said wider sections defining the contour of said wider sections as pin ticket bodies whereby 110 severance upon the fold lines on the same side of successive wider sections will produce pin tickets each having a laterally extending flap and identical notations upon the successive narrow and wide sections. 115

In testimony whereof, I have signed my name to this specification.

ALONZO KIMBALL MARSH.
